UNITED STATES PATENT OFFICE

JOSEPH LEON BERGERON, OF QUEBEC, QUEBEC, CANADA

SCREEN ROLL

Application filed December 10, 1928. Serial No. 324,893.

The invention relates to a screen roll, as described in the present specification and illustrated in the accompanying drawings that form part of the same.

5 The invention consists essentially of the novel features of construction pointed out broadly and specifically in the claims for novelty following a description containing an explanation in detail of an acceptable 10 form of the invention.

The objects of the invention are to eliminate the frame or frames within cylindrical rolls, particularly those formed of wire mesh or other like material, and support the cylinder entirely from the end or head by maintaining the screen in tension throughout; to avoid irregularities on the sheet of pulp in paper making due to the deposit of dirt or other particles or loose ends frequently picked up and redeposited by dandy rolls; to facilitate the operation of dandy rolls so that there will be no slip or drag, and no separation of the fibres from the pulp, and at the same time insure that the roll will always be 15 in a cleanly condition thereby maintaining an even surface and an even thickness of the sheet being produced; to do away with dented, creased or rolls otherwise deformed by enabling the operator to replace a roll 20 with great facility or straighten the roll out and keep it so by constant pull on the ends thereof; to drive a roll without distortion of the light material and yet drive it entirely to one end thereof; to produce a roll for 25 special uses in industrial pursuits that will keep its shape under most conditions without being encumbered by an interior frame; and generally to provide at a moderate cost of production a screen roll, light and durable 30 and efficient in operation.

In the drawings, Figure 1 is a front elevational view of the screen roll and expanding frames.

Figure 2 is an elevational view showing 45 the frame at one end and driving mechanism.

Figure 3 is an elevational view showing the frame at the other end.

Figure 4 is a longitudinal sectional view 50 of the screen roll showing the driving mechanism on the line 4-4 in Figure 2.

Figure 5 is a longitudinal sectional view of the screen roll and contiguous parts on the line 5-5 in Figure 2.

Figure 6 is a cross sectional view on the line 6-6 in Figure 1.

Figure 7 is a sectional detail of the slide mounting of the frame.

Like numerals of reference indicate corresponding parts in the various figures.

In the description hereinafter given in this invention, the use of the screen roll will be confined to its operation in paper making, that is to say, it will be explained that this screen roll is particularly adaptable as a dandy roll, though nothing hereinafter mentioned need in any way confine the invention to this particular purpose.

Referring to the drawings, the dandy roll herein illustrated is in the form of a cylindrical screen 15 of wire mesh secured on the ring flanges 16 and 17 at the ends, said flanges being preferably in the form of a disc surrounding the hubs 18 and 19 screwed on to the trunnions 20 and 21, and forming the heads and journal members of a rotating screen drum.

The driving bevel gear 22 is part with the transmission spur gear 23, and these two gears are secured through their web 24 by the bolts 25, to the flanges 16 and 17 and are mounted through their hub 26 on the trunnion 20 and secured thereon by the key 27.

The transmission spur gear 28 is secured by the bolts 29 to the flange 17 and is mounted by means of the hub 30 on the trunnion 21 and secured thereto by the key 31.

The sliding bearing frames 32 and 33 carry the trunnions 20 and 21 respectively and are locked thereon by the end thrust bearings 34 and 35 respectively screwed to the trunnions.

The sliding bearing brackets 32 and 33 extend upwardly and are slidably mounted on the fixed brackets 36 and 37 having the dovetails 38 mounted on the dovetail grooves 39 and the adjusting wedge pins 40 used in adjusting the sliding connections of the sliding and fixed brackets.

The brackets 32 and 33 flare outwardly on each side forming in the bracket 33 supports for the rod 42 extending from the pistons 43.

The cylinders are connected by the feed pipes 44 to a suitable supply of expansile fluid, therefore it will be seen that on feeding air or steam into the cylinders 41 the pistons will be driven outwardly carrying the rods 42, and as the rods 42 are fixedly secured to the bracket 32 and the cylinders 41 fixedly secured to the bracket 33, naturally the brackets will be forced apart on each side 5 of the screen 15, thus pulling on the screen from the ends, as the screen is firmly held to said brackets by the thrust bearings 34 and 35, consequently any inequalities of the screen must be immediately smoothed out by 10 the constant tension on said screen applied through the said cylinders and pistons operating therein.

The spray pipe 45 having the jet orifice 46 extends through the hollow trunnions 20 and 21 and out through the casings 47 and 48 enclosing said trunnions and thrust bearings 34 and the roller bearings 49, and it is by means of this spray pipe that the wire mesh screen is kept in a cleanly condition.

25 The drip pan 50 is supported from the brackets 32 and 33 and extends partly under the screen so that all the water sprayed on the inner wall of the screen will be caught by said pan.

30 The transmission spur gears 51 and 52 coact with the transmission gears 23 and 28 respectively, and are mounted on the common shaft 53 journalled in the brackets 32 and 33.

35 The driving bevel is driven by the coacting driving bevel 54 mounted on the main shaft 55, which is connected to any suitable power, thus when the bevel gear 22 is driven the transmission gear 23 rotates therewith as 40 it is part thereof, and as the transmission gear 23 coacts with the transmission gear 51, the transmission gear 52 must coact with the transmission gear 28, thus the motion from the driving bevel gear 54 is transmitted to the opposite end of the screen roll 45 thereby avoiding the distortion of the roll through the driving at one end only.

The main shaft 55 is journalled in the bearings 56 on the sliding bracket 33 and 50 diametrically opposite the main shaft and main driving bevel gear.

The bevel gear 57 coacts with the bevel gear 22 and is mounted on the shaft 58 slideable in the bearings 59 secured to the bracket 55 32 and locked therein by hinged strap 60.

The shaft 58 at its outer end carries the hand wheel 61 by means of which the bevel 60 gear 57 is turned to rotate the screen roll, in the assembling of the parts, but during the operation, the bevel gear 57 is removed from coaction with the bevel gear 22 and drawn completely away therefrom, so that it is quite out of the way during the operation of the dandy roll in paper making.

65 In the assembling and in the operation of

this machine, the cylindrical roll of wire mesh is mounted on the end flanges which are screwed on to the trunnions, these trunnions being mounted in bearings in the slideable brackets and held securely in said brackets by end thrust bearings.

These brackets are connected by the pistons and cylinders and are slidably mounted on the fixed brackets, consequently when the parts are all assembled, the pistons are operated in the cylinders by means of expansile fluid and the brackets supported to the fullest extent that the screen drum or roll will allow, and in consequence of this the wire mesh is continuously in tension.

The driving bevel gear on the main shaft and the coacting driving bevel gear on the screen insure the rotation of said screen on the wire of the Fourdrinier machine, and as this dandy roll is driven it smooths out the sheet of pulp passing and squeezes out excess water and generally performs all the functions that a dandy roll usually performs, the salient features of this particular dandy roll being the means of maintaining the wire mesh in constant tension and thereby eliminating an interior frame, the means of keeping the wire mesh roll in a cleanly condition, and the means of avoiding the effects of distortion and driving from one end and the constructional features whereby the roll may be removed for repair and replaced with great facility.

All of these features are very important and may constitute novel elements both in a dandy roll form of machine and in any other screen roll used for other purposes.

What I claim is:

1. In a screen roll, a drum having a cylinder formed of suitable light material and heads of heavier material, and means for expanding said heads in relation to the drum cylinder.

2. In a screen roll, a drum having a cylinder of wire mesh and heads of heavier material and means for expanding said heads in relation to the drum cylinder.

3. In a screen roll, a drum having a wire mesh cylinder mounted on end flanges and supported centrally from said flanges, and means for expanding said flanges in relation to the drum cylinder.

4. In a screen roll, a drum having a wire mesh cylinder terminating at each end in solid rings suitably supported from a central bearing and means for expanding said rings in relation to the drum cylinder.

5. In a screen roll, a drum having a wire mesh cylinder and solid rings at the ends thereof and gear members supporting said rings and suitably journalled, and means for expanding said rings in relation to the drum cylinder.

6. In a screen roll, a drum having a wire mesh cylinder and end flanges, gears secured

to said flanges and suitably journalled, coacting gears and shaft mounting suitably journalled, means for driving said drum, and means for expanding said flanges in relation 5 to the drum cylinder.

7. In a screen roll, a cylindrical wire mesh screen having sliding end mountings and means therewithin for expanding said mountings.

10 8. In a screen roll, a cylindrical wire mesh screen having sliding end mountings and trunnions therefrom, means for driving said screen, and means for maintaining said mountings in an extended position and the 15 screen in tension.

9. In a screen roll, a cylindrical wire mesh screen having solid end flanges, gears secured to said flanges and having trunnions therefrom and forming driving transmission gears 20 having a common shaft mounting suitably journalled and avoiding distortion of the roll, a coacting driving gear suitably journalled and driven and means exerting a continuously spreading pressure on said flanges 25 and said gears to maintain said screen in tension.

10. In a screen roll, a cylindrical wire mesh screen having heads of heavier metal in the form of gears and flanges and trunnions 30 therefrom, sliding brackets forming bearings for said trunnions, fixed brackets supporting said sliding brackets and means for exerting an end pull on the roll ends from said sliding brackets and for maintaining said screen in 35 tension.

11. In a screen roll, a cylindrical wire mesh screen having journal members secured to the ends thereof, sliding brackets forming bearings for said journal members, fixed brackets 40 having slideways for said sliding brackets, gear mechanism mounted in said sliding brackets and on said journal members and screen, means for driving said gear mechanisms and means for exerting continuous outward pull on said journal members from said 45 sliding brackets.

12. In a screen roll, a cylindrical wire mesh screen having journal members secured to the ends thereof, bearings for said journal members automatically adjustable and means contiguous to the roll cylinder for exerting constant tension thereon and coincidently adjusting said bearings.

13. In a screen roll, a cylindrical wire mesh 55 screen demountably secured to journal members, adjustable bearings for said journal members and expansile means for exerting pull on the journal members and for maintaining the screen in tension.

60 14. In a screen roll, a cylindrical wire mesh screen secured to journal members, bearings slidably mounted, and a cylinder and piston respectively mounted on said bearing and connected to an expansile fluid supply.

65 15. In a screen roll, a drum having a cyl-

inder formed of wire mesh and heads of heavier material, pistons operatively connected to one head and cylinders connected to a suitable fluid supply and operatively connected to the other head and expanding said drum lengthwise through the endwise expansion of the heads.

70 16. In a screen roll, a cylindrical screen, a driving gear at one end thereof, a coacting driving gear, a coacting adjusting gear and operating gear mounted in a bracket having a manually operated shaft for withdrawing the adjusting gears from coaction and flange mountings for said screen secured to said coacting adjusting gear in its adjusted position.

75 17. In a device of the kind described, a screen and means operatively connected with the ends of the screen and exerting a continuous pull thereon in opposite directions while the screen is in operation.

Signed at Quebec this seventeenth day of November, 1928.

JOSEPH LEON BERGERON.
